(57) **CLAIM**

The ornamental design for a platform for holding one adornment applied to an apertured orthopedic support, as shown and described.

DESCRIPTION

FIG. 1 is a perspective view of a platform for holding one adornment applied to an apertured orthopedic support;

FIG. 2 is a second perspective view thereof;

FIG. 3 is a top view thereof;

FIG. 4 is a bottom view thereof;

FIG. 5 is a left side view thereof;

FIG. 6 is right side view thereof;

FIG. 7 is a rear view thereof;

FIG. 8 is a front view thereof; and,

FIG. 9 is an assembled view thereof.

The broken lines in the drawings depict environmental subject matter and form no part of the claimed design.
